UNITED STATES PATENT OFFICE

PER A. PETERSON, OF NEW YORK, N. Y.

AEROPLANE

Application filed May 16, 1930. Serial No. 452,863.

My invention relates to aeroplanes.

The object of my invention is to provide means for removing frost and snow from the edges and upper side surfaces of the wings by mechanical means.

Referring to the drawings which form a part of these specifications:

Fig. 1 is a plan view of the body and wings of an aeroplane, showing one form of my device mounted thereon.

Fig. 2 is a side view.

Fig. 3 is a cross sectional view on line 3—3 of Fig. 1.

Fig. 4 is a cross sectional view thru the wings, on line 4—4 of Fig. 1.

Fig. 5 is a side view, taken on line 5—5 of Fig. 1, the side of the body portion being shown partly in section to disclose the mechanism mounted therein.

Fig. 6 is a cross sectional view, taken on line 6—6 of Fig. 5, thru the body and wings of the machine.

Fig. 7 is a sectional plan view, taken on line 7—7 of Fig. 6.

10— indicates the body portion of the aeroplane, which may be made in the usual manner heretofore known, on which my device may be installed.

11— indicates the wings of the plane.

12— indicates a pair of V-shaped scrapers, which are mounted on the upper ends of shafts 13— which extend thru the top 14— of the body portion, and are formed square in cross section as illustrated at 15—.

16— Hub-plates 16— having a depending hub portion 17— are carried by the shafts 13—, the hub being formed to fit over the squared ends of the shafts, as shown. The scrapers 12— are mounted on the hub plates and riveted or otherwise suitably attached firmly thereto, and nuts 18— are screwed on the shafts above the scrapers to hold the parts together in separable relation, but if preferred, the said parts may be permanently connected by welding, or other proper process.

17— The scrapers are preferably made of strong sheet aluminum alloy, and are supported on the shafts so that the outer scrap- 50 ing edges of the scrapers may be moved over

the top of the wings in close proximity to the surface thereof out of contact therewith.

18— The outer edges of the scrapers are formed with downwardly extending walls 19—, which serve to stiffen and strengthen the construction.

19— Attached to the ends of the wings are slotted metal guide members 20— thru which the ends 21— of the scrapers project, to guide and support the scrapers. These guide members are attached to the frame which supports the wing covering material, and may be made of sheet metal or cast in aluminum alloy.

20— The middle portions of the scrapers are cut away as shown in Figure 1—, to reduce the weight, and also to remove as much top surface as possible, on which snow might otherwise collect. The adjacent end portions of the scrapers extend beyond the front 70 and back edges of the wings, as shown at 22— so that the edge portions 23— will extend beyond the edges 24— and 25— of the wings, when in operation.

21— Spring buffers 26— are attached to the 75 wings and rest in the path of the scrapers as illustrated, to prevent shock, as will be readily understood.

22— A flange 27— is carried on the lower end of each of the shafts 13—, and rest on ball 80 bearings 28— which in turn rest in a groove formed in the upper side of a flange 29— supported on the floor of the body portion.

23— Connected to each shaft 13— is an arm 85 30—, on which is mounted a casting 31— provided with a bifurcated extension in which is fitted one end of a connecting-rod 32— held by a wrist-pin 33—. 34— indicates pillar blocks, having bearings in their upper ends for a cross-shaft 35— which extends there thru and carries a crank 36— on each end, which are connected in operative relation with the connecting-rods 32—.

24— A shaft 37— driven by the engine which drives the propeller 38—, carries a clutch 39— near its free end, which slides on the shaft 37— and is driven by a feather in the usual way, and is operated by a hand-lever 40— thru the lever elements 41— and 42—, as will be readily understood.

Mounted on the shaft is a pinion gear wheel 43—driven by the clutch member, and in mesh with a larger gear wheel 44—fixed on the shaft 35—to drive said shaft at a reduced speed.

While I have shown a construction which embodies my invention, I am aware that a number of changes and modifications may be made if desired. The buffers 26—may be 10 dispensed with and equivalent means for this purpose may be connected to the shafts 13—in the form of shock-absorbers. Also, the scrapers may be provided with gear teeth on their adjacent edges 45—and 46—and are 15 ranged in mesh so that one shaft 13—may drive both scrapers. Also the scrapers may be joined together and driven by a single shaft connected at its centre, one edge of a 20 scraper over one wing being at the front edge of the wing while the back edge of a scraper over the other wing, is at the back edge thereof, etc.

Such changes are easily understood by those skilled in the mechanical arts.

25 The operation of the present construction herein shown, is as follows:

Assuming the engine to be running, and the clutch disconnected; the operator pulls the lever 40—to draw the clutch member 30 39—in gear, thus transmitting power to pinion 43—, gear wheel 44—, shaft 35—and cranks 36—to the connecting rods 32—and shafts 13—, to impart motion to the scrapers 12—, as will be readily understood.

35 In cold climates, when it snows, the front edges of the wings collect snow and ice, and snow and ice also settle on the top of the wings thus making it dangerous for the pilot in handling the machine, and the present invention is designed to prevent such collection by cutting under the snow and thus permitting the air currents to carry it away.

40 Having thus described my invention, I claim as new:

45 1. An aeroplane comprising a body portion, wings thereon, a scraper mounted above said wings adjacent thereto, and means for moving said scraper.

50 2. An aeroplane comprising a body portion, wings thereon, a scraper mounted above said wings adjacent thereto, and means for transmitting motion to said scraper.

3. As stated in claim 2; and driving means 55 comprising a clutch for connecting said scraper in separable relation therewith.

4. As stated in claim 1; and guide members for guiding and supporting the scraper.

5. An aeroplane comprising a body portion, wings thereon, a scraper mounted above said wings adjacent thereto comprising two scraper elements, and means for transmitting motion from a source of power to said elements.

65 6. As stated in claim 5; and means for

guiding and supporting said scraper elements.

7. An aeroplane comprising a body portion, wings thereon, two shafts extending above said wings, a scraper element mounted 70 on the upper end of each of said shafts adjacent to the upper side of said wings, and means for transmitting motion from a prime mover to said shafts to move said scrapers.

8. As stated in claim 7; and means for 75 guiding and supporting said scrapers.

9. An aeroplane comprising a body portion, wings thereon, shafts extending above said wings, scraper elements mounted on said shafts, means for transmitting movement to said shafts and alternately reverse the rotational movement thereof, and means for guiding and supporting said scraper elements.

10. As stated in claim 9; and shock absorbing means for said scraper elements.

In testimony whereof I have affixed my signature.

PER A. PETERSON.
